G. KRELL

WELL TUBING ELEVATOR

Filed June 9, 1923

UNITED STATES PATENT OFFICE.

GEORGE KRELL, OF KANSAS CITY, MISSOURI.

WELL-TUBING ELEVATOR.

Application filed June 9, 1923. Serial No. 644,937.

To all whom it may concern:

Be it known that I, GEORGE KRELL, a citizen of Germany, residing at Kansas City, in the county of Jackson and State of Missouri, U. S. A., have invented certain new and useful Improvements in Well-Tubing Elevators; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a well tubing elevator; that is, to an elevator for "pulling" and lowering well tubing and like casings.

The device is not primarily intended as a casing elevator although it may be used for "pulling" casing of smaller diameters. It is intended more particularly for handling the tubing or pipe through which oil is pumped from the well, the primary object being to provide an inexpensive, easily constructed elevator and to this end the invention consists in certain parts and combinations of parts, all of which will be specifically referred to hereinafter, reference being had to the accompanying drawings, in which Fig. 1 is a perspective view of an elevator constructed in accordance with my invention.

Fig. 2 is a side elevational view of the same.

Fig. 3 is a vertical, sectional view through the elevator, and

Fig. 4 is a plan view, the link connections, one end of each side bar, and the connection for one rotor arm being shown in section.

Fig. 5 is a disassociated perspective view of one of the jaw members and its associated rocker arm.

The invention may include a frame consisting of side bars 1 and 2 and end shafts 3 and 4. The end members or shafts 3 and 4 extend through the collars or heads 5 and 6, 7 and 8, the heads being held in place by the plates 9, 10, 11 and 12.

On the shafts 3 and 4 are inverted U-shaped links 13 and 14 having spaced ends with collars 15, 16, 17 and 18 through which the shafts 3 and 4 extend. Between the collars of the links are collars 19 and 20 of the rocker arms 21 and 22. The rocker arms extend upwardly and inwardly, and they have transverse heads 23 and 24, which

engage transverse sockets 25 and 26 in the jaw members 27 and 28. Each jaw member is substantially semi-circular and each socket is provided at its lower portion with lateral lugs or projections 29 and 30, which straddle the arms 21 and 22 so as to hold the arms and jaws in operative positions. This will be apparent by reference to Figs. 1 and 5.

The jaw members may be held in proper position with respect to one another by the pin 31 which passes through the lugs 32 and 33 so that the jaw-engaging faces will at all times be in substantially vertical planes. The jaws may be opened by a link mechanism comprising an elbow lever 34 on the shaft 3 and having link levers 35 and 36 connected to the respective jaws.

The important feature of this invention is the manner of mounting the jaws; that is, providing a single lever for each jaw and loosely supporting the jaws so that they will be self-seating upon the tube which they are to engage.

Removable liners 37 and 38 may be provided for the jaws so that the jaws may be adapted to engage tubes of different diameters.

The jaws may be opened through the medium of the elbow lever 34 and links 35 and 36 to slip over the tube; then the jaws will engage the tube, being self-seating so that they will firmly grip the outside wall thereof, whereupon the elevator can be lowered or raised, dependent upon whether the tubing is to be lowered or "pulled".

When the tubing is in place, the elevator can be taken off by opening the jaws through the medium of the elbow lever 34.

An elevator for oil well casing of the same general type of the present construction has been patented to me on February 27, 1923 and given No. 1,446,568, so I do not lay any claim to any broad embodiment of links, rocking levers or self-seating jaws in this application, the invention consisting rather in the simplified construction which enables me to produce a less expensive elevator than can be produced under my prior patent.

What I claim and desire to secure by Letters Patent is:

1. In a well tubing elevator, a frame, single rocker arms on the respective ends of the frame, jaws loosely mounted on the inner ends of the rocker arms, and means for supporting the frame.
2. In a well tubing elevator, a frame, sin-

gle rocker arms on the respective ends of the frame, jaws loosely mounted on the inner ends of the rocker arms, and means for supporting the frame, said means comprising bails connected to the ends of the frame on opposite sides of the rocker arms.

3. In a well tubing elevator, a frame, single rocker arms on the respective ends of the frame, jaws loosely mounted on the inner ends of the rocker arms, means for supporting the frame, and jaw-opening means carried by the frame.

4. In a well tubing elevator, a frame comprising side bars and end shafts connected to the side bars, inverted U-shaped links connected to the shafts with their ends in spaced relation, single rocker arms loosely mounted on the respective shafts between the ends of the links, and jaws loosely mounted upon the inner ends of the rocker arms.

5. In a well tubing elevator, a frame comprising side bars and end shafts connected to the side bars, inverted U-shaped links

connected to the shafts with their ends in spaced relation, single rocker arms loosely mounted on the respective shafts between the ends of the links, jaws loosely mounted upon the inner ends of the rocker arms, and jaw-opening mechanism carried by one of the shafts.

6. In a well tubing elevator, a frame, having side bars and end members connecting them, headed rocker levers loosely mounted on the end members, and jaws having sockets into which the heads of the rocker levers are received.

7. In a well tubing elevator, a frame having side bars and end members connecting them, headed rocker levers loosely mounted on the end members, transverse heads on the inner ends of the rocker levers, jaws having transverse recesses receiving the heads, outwardly projecting lugs carried by the jaws overlapping the sides of the rocker levers, and means for supporting the frame.

In testimony whereof I affix my signature.
GEORGE KRELL.
